C. BERTHOLD.
LOCK VALVE DEVICE,
APPLICATION FILED DEC. 18, 1916.

1,244,691.

Patented Oct. 30, 1917.

FIG. 3.

Inventor
Charles Berthold,
By his Attorneys

Edgar A. L. Co.

UNITED STATES PATENT OFFICE.

CHARLES BERTHOLD, OF RICHMOND HILL, NEW YORK.

LOCK-VALVE DEVICE.

1,244,691.

Specification of Letters Patent. Patented Oct. 30, 1917.

Application filed December 18, 1916. Serial No. 137,498.

To all whom it may concern:

Be it known that I, CHARLES BERTHOLD, a citizen of the United States, and residing at Richmond Hill, L. I., in the county of 5 Queens and State of New York, have invented certain new and useful Improvements in Lock-Valve Devices, of which the following is a specification, such as will enable those skilled in the art to which it appertains to 10 make and use the same.

This invention relates to lock valve devices for use in the gasoline supply pipe of an automobile engine, and the object thereof is to provide an improved device of this 15 class that can only be operated by the owner of the vehicle so as to prevent the stealing of the vehicle, or the use thereof, without the owner's knowledge or consent; a further object being to provide a combination valve 20 device of the class described which is placed in the gasoline supply pipe between the supply tank and the carbureter of the engine; and with these and other objects in view the invention consists in a device of the class 25 specified constructed and operating as hereinafter described and claimed.

The invention is fully disclosed in the following specification, of which the accompanying drawing forms a part, in which 30 the separate parts of my improvement are designated by suitable reference characters in each of the views, and in which:—

Figure 1 is a sectional view showing my improved valve device and the method of 35 its use;

Fig. 2 a plan view of the valve device detached but showing the gasoline supply pipe, part of the construction being in section; and,

Fig. 3 a side view of one of a number of 40 valves which I employ.

In the drawing forming part of this specification, I have shown at *a* the floor board of an automobile, and at *b* the pipe 45 which connects the gasoline supply tank of the engine with the carbureter and, in the practice, of my invention, as shown in the drawing, I provide an oblong valve casing *c* having end neck members *c*² provided with central bores *c*³ and, in practice, the pipe *b* is divided to form end portions which are 50 screwed into the necks *c*² of the valve casing as shown.

The valve casing *c* is provided with circular valve chambers *c*⁴, three of which are 55 employed in the construction shown, and in

which are mounted cylindrical valves *d* having stems *d*². The valve chambers *c*⁴ open through the top of the valve casing and are provided with detachable caps *c*⁵ which are 60 screwed into said valve casing and which close the valve chambers *c*⁴, and which are provided with tubular necks *c*⁶ which pass upwardly into or through the floor board *a*, and the stems *d*² of the valves *d* are 65 provided with caps *d*³ which are secured to said stems and are provided with transverse apertures *d*⁴, and the valves *d* are operated by a key inserted into said apertures.

The end valve chambers *c*⁴ communicate 70 with the end bores *c*³ in the necks *c*² of the valve casing; and the separate valve chambers are placed in communication by other bores or passages *c*⁷, and the valves *d* are provided with a plurality of radial ports 75 or passages *d*⁵, all of which are in communication and which are also adapted to communicate with the ports or passages *c*³ and *c*⁷ in the valve casing, and with this construction, when the said valves *d* are in 80 proper position, the gasoline is free to pass through the pipe *b* from the gasoline tank to the carbureter.

The caps *d*³ of the valve stem *d*² serve as dial plates and are provided with numerals 85 which, in the construction shown, range from zero to seven; and the tubular necks *c*⁶ are provided on the face thereof with radial pointer marks *c*⁸, and in the use of my improved valve device the outer ends of the 90 radial ports or passages *d*⁵ in the valves *d*, with the exception of two, which are oppositely arranged, in the construction shown, are all closed by screw-threaded plugs *d*⁶.

The valve chambers *c*⁴ are also preferably 95 provided in the bottom thereof with tension springs *e* which serve to force the valves *d* upwardly and insure a tight contact thereof with the caps *c*⁵ of the valve chamber *c*⁴ and also hold said valve in proper position, 100 but these springs are not absolutely necessary and the valve devices *d* may be made to exactly fit the valve chambers in which they are placed.

The arrangement of the numerals on the 105 dial plates or heads *d*³ of the stems *d*² of the valves correspond with the arrangement of the ports or passages *d*⁵ in said valves, and by reason of this fact the said valves may be turned by means of a key so that 110 either two of the ports therein will be in the position shown at the right of Fig. 2,

and the gasoline will be free to pass through the valve device as will be readily understood. By shifting the plugs ^d different ports or passages in the valves may be employed to complete the desired combination, and in this way any desired combination of such ports or passages may be used, and the combination thus formed will only be known to the owner of the machine, or to one who will be entitled to such knowledge, and who will be in possession of the key for operating the valves, and only such party or parties can for this reason operate the machine, as will be readily understood, and my improved valve device will thus serve not only to prevent the stealing of the machine, but to prevent the use thereof without the knowledge or consent of the owner.

It will be understood that my improved valve device may involve any desired number of valves, and changes in and modifications of the construction herein described and the method of operating the same may be made, within the scope of the appended claims, without departing from the spirit of my invention or sacrificing its advantages.

Having fully described my invention, what I claim as new and desire to secure by Letters Patent, is:—

30. 1. A combination valve device of the class described, comprising a valve casing having a plurality of valve chambers all of which communicate through ports or passages in said casing, and valves placed in said chambers and provided each with a plurality of radial ports or passages, all of which are in communication and adapted to be placed in communication with the ports or passages in the valve casing, the ports or passages in each valve with the exception of two, being closed by detachable plugs, and said valves being also provided with stems having dials bearing numerals which correspond with the radial ports or passages in said valves.

45. 2. A valve device comprising a casing, a plurality of valve members mounted therein each of said valve members being provided with a plurality of ports or passages, means for manipulating said valve members to bring a part of the ports or passages in one valve member into communication and alignment with a part of the ports or passages of the other valve members, and means for sealing the other ports or passages in said valve members.

50. 3. The combination in a valve device of the class specified, of a casing having a plu-

rality of valve chambers, all of which are in communication, and valves in said chambers, each of said valves being provided with a plurality of radial ports or passages all of which are in communication and all of which are adapted to be placed in communication with ports or passages in the valve casing, all of said radial ports or passages in each valve except two being sealed when the valve device is in use.

4. A valve device, comprising a casing having a plurality of valve chambers, all of which are placed in communication by ports or passages in said casing, and valves mounted in said chambers and provided each with a plurality of radial ports or passages all of which are in communication, said ports or passages being greater in number than two, and means for sealing all of said radial ports or passages in each valve except two when the valve device is in use.

5. A valve device comprising a casing having a plurality of valve chambers, all of which are placed in communication by ports or passages in said casing, and valves mounted in said chambers and provided each with a plurality of radial ports or passages all of which are in communication, said ports or passages being greater in number than two, and means for sealing all of said radial ports or passages in each valve, except two when the valve device is in use, said valves being also provided with stems having dial plates provided with numerals which correspond with the radial ports or passages in the valves.

6. In a valve device of the class described, a valve having a plurality of radial ports or passages all of which are in communication and which are greater in number than two, and devices for sealing all of said ports or passages except two when the valve is in use.

7. In a valve device of the class described, a valve having more than two radial ports or passages all of which are in communication, and interchangeable devices for sealing all of said ports or passages except two when the valve device is in use.

In testimony that I claim the foregoing as my invention I have signed my name in presence of the subscribing witnesses this 15th day of December 1916.

CHARLES BERTHOLD.
